ELECTRICAL HEATER

Filed Feb. 19, 1929

UNITED STATES PATENT OFFICE

OTTO D. THORSNESS AND DEWEY R. TOWER, OF LAKE PRESTON, SOUTH DAKOTA, AS
SIGNORS TO ELECTRIC HEATING DEVICES, INC., OF LAKE PRESTON, SOUTH DAKOTA,
A CORPORATION OF SOUTH DAKOTA

ELECTRICAL HEATER

Application filed February 19, 1929. Serial No. 341,117.

This invention relates to electrical heaters, and more particularly to heaters for insertion in the water circulation systems of automobile engines for heating the water of the system during extremely cold weather to thereby facilitate starting of the car or to prevent freezing of the water in the system during periods when the engine is idle.

An important object of the invention is to produce a device of this character which will be highly efficient in operation and which, at the same time, may be very readily and cheaply manufactured and may be very readily installed in the engine.

15 A further object of the invention is to provide a construction such that a maximum transfer of heat from the heating coil to the water system is obtained.

These and other objects we attain by the construction shown in the accompanying drawings, wherein for the purpose of illustration is shown a preferred embodiment of our invention and wherein:—

Figure 1 is a plan view of a heating element constructed in accordance with our invention;

Figure 2 is a section on the line 2—2 of Figure 1.

Figure 3 is a section on the line 3—3 of Figure 1.

Referring now more particularly to the drawing, the numeral 10 indicates a tube, the ends of which are slightly tapered in exterior diameter, as indicated more clearly at 11, so that they may be readily inserted in the flexible hose connection 12 commonly employed for connecting the radiators and engines of internal combustion engines.

40 This tube has a central portion thereof provided with inwardly extending longitudinally directed ribs 13. About this central portion of the tube is placed a layer of thin flexible insulating material, such as mica, as indicated at 14, upon which is wound a heating coil 15. The mica and heating coil are anchored in position by means of asbestos or other insulating cement 16 which is placed over the coil and mica in a thin layer

45 which engages at its ends with the tube and

seals thereto so that there is no possibility for escape of the coil.

Upon the tube at opposite ends thereof are placed collars 17, each having an inwardly directed peripheral flange 18. A cylindrical wall casing 19 is provided, this casing being of considerably greater diameter than the outside of the cement layer, so that a space 20 is formed therebetween. One end of this cylindrical wall is formed with a notch 21 receiving an insulating block of some heat resistant insulating material, such as slate, porcelain or the like.

The side and end walls of the block are grooved, as at 22, so that this block may be 55 slid into the groove but when in position, may not move transversely of the housing. The flange coacting with this end of the housing is likewise notched, as indicated at 23, to receive the block. This block mounts 60 binding posts 24 to which the ends of the heating coil are electrically connected. The space 20 is filled with some cellular heat and electrical insulating material, such as asbestos, which serves at once to prevent the escape 65 of heat generated in the coil through the casing walls and to prevent electrical contact of the lead wires with the walls of the casing.

It will be obvious that a device of this 70 character may be very readily and cheaply constructed and may be very readily inserted in the water circulation system of the automobile. It will also be obvious that the construction hereinbefore set forth is capable 75 of a certain range of change and modification without materially departing from the spirit of the invention and we accordingly do not limit ourselves to such specific structure except as hereinafter claimed.

We claim:—

1. In a heater of the type described, a metallic tube having tapering opposite end portions whereby to permit mounting of the tube in a flexible conduit, an electrical heating element surrounding the tube and secured against shifting movement thereon, a casing surrounding the tube and sealed at its ends thereto, said casing having the walls thereof in spaced relation to the electrical 80

heating element and having the opposite ends thereof spaced inwardly of the opposite ends of the tube, and a filling of heat and electrical insulating within the casing about the heating element, the inner wall of said tube having inwardly projecting radiation ribs.

2. In a heater of the type described, a metallic tube having tapering opposite end portions whereby to permit mounting of the tube in a flexible conduit, an electrical heating element surrounding the tube and secured against shifting movement thereon, a casing surrounding the tube and sealed at its ends thereto, said casing having the walls thereof in spaced relation to the electrical heating element and having the opposite ends thereof spaced inwardly of the opposite ends of the tube, a filling of heat and electrical insulating within the casing about the heating element, said heating element comprising an inner layer of flexible insulating material directly engaging the tube, a coil wound upon said insulating material, and a layer of insulating cement covering the insulating material and coil and engaging with the wall of the tube at its ends, the inner wall of said tube having inwardly projecting radiation ribs.

30 In testimony whereof we hereunto affix our signatures.

OTTO D. THORSNESS.
DEWEY R. TOWER.
